WESTON M. FULTON, OF KNOXVILLE, TENNESSEE, ASSIGNOR TO THE FULTON COMPANY,
OF KNOXVILLE, TENNESSEE, A CORPORATION OF MAINE.

CARBURETER.

1,145,476.

Specification of Letters Patent.

Patented July 6, 1915.

Application filed April 11, 1913. Serial No. 760,491.

To all whom it may concern:

Be it known that I, WESTON M. FULTON, of Knoxville, Tennessee, have invented a new and useful Improvement in Carbureters, 5 which invention is fully set forth in the following specification.

This invention relates to carbureters designed for use with internal combustion engines, and more particularly to that class of 10 carbureters wherein means are employed for controlling the temperature of the incoming air or of the outgoing air and combustible vapor.

The primary object of the invention is to 15 provide in a carbureter, in which the temperature of the incoming air is maintained practically uniform, automatic means for controlling supply of the liquid fuel to the air passing through the carbureter whereby 20 an approximately uniform mixture of air and combustible vapor is delivered to the engine to give therein, at all times, the maximum explosive effect of the mixture without requiring attention of the operator to manually 25 adjust the supply of vapor to the air.

A further object of the invention is to enable a mixture of air and combustible vapor in predetermined proportions to be delivered to the engine without attention of the 30 operator whatever may be the speed of the engine.

A further object of the invention is to maintain a substantially constant composition of the explosive mixture delivered to 35 the engine in the manner above stated, and at the same time to regulate the temperature of this mixture by the automatic control of the liquid fuel vaporized into the air current passing through the carbureter whereby 40 greater power and smoother running is secured in the engine.

The above and other objects will be more fully explained in the detailed description.

Heretofore carbureters have been provided 45 with auxiliary means for maintaining the temperature constant of the incoming air or of the outgoing mixture of air and hydrocarbon vapor. This result is usually attained by uniting currents of hot and 50 cold air and controlling the relative quantity of each by means of a thermosensitive element located in some part of the path traversed by the united currents either before or after the point where the hydrocarbon is introduced. While such means under favor-

able conditions and expert attention are quite satisfactory for the purpose of securing constant temperature of the mixture delivered to the engine, they are not adapted for controlling the supply of hydrocarbon 60 admitted to the carbureter or air current and do not prevent the well-known waste of hydrocarbon due to the variation of the relative amounts of air and vapor delivered to the engine. 65

My invention is applicable to any form of carbureter employing means for controlling the temperature of the incoming air and accomplishes the above objects by providing in combination a carbureter having means for 70 controlling the temperature of the incoming air and thermosensitive means subject to the influence of the temperature of the mixture of air and hydrocarbon or other inflammable vapor for controlling the supply of the carbureting medium whereby the composition of the combustible mixture may be maintained substantially constant for all demands on the carbureter. This arrangement will also maintain the temperature of 80 the combustible mixture substantially constant. 75

The invention also provides adjusting means which are associated with thermosensitive means for enabling a mixture of air 85 and vapor in predetermined proportions to be at all times delivered by the carbureter.

In the accompanying drawing, I have shown one constructional form of my invention, but such drawing is intended merely as 90 an illustration to assist the description and not as defining the limits of the invention.

The figure in the drawing is a vertical central sectional view with interior parts in elevation of a carbureter provided with my 95 improvements.

The carbureter casing is preferably constructed in U-tube form and of three cast metal sections: a lower or base section 1 associated with a liquid fuel reservoir, an intermediate section 2 resting on and suitably secured to the lower section and a top section 3 suitably secured to the intermediate section 2 and provided with an air intake 4 and a discharge outlet 5. The lower section 100 1 is provided with a liquid fuel reservoir 6 of annular form in which is located a float 7 or similar form fast to one end of a pivoted lever 8, to the opposite end of which lever is connected a needle valve 9 through 105 110

adjusting means 10. This valve controls supply of liquid fuel to the reservoir through a supply pipe 11. Leading from the annular fluid reservoir 2 into the space 5 of the carbureter casing is a duct 12 preferably having an upturned delivery end controlled by a needle valve 13 provided with a guide pin 14.

For the purpose of controlling the temperature of the air entering the carbureter any means suitable for the purpose may be employed. By way of illustration, I have shown one form of device well adapted for the purpose, but make no claim to its specific construction. This device comprises a conduit 15 provided with a flange portion 16 adapted to be secured to a corresponding flanged portion 17 on the air intake member 4 of the carbureter by means of bolts 18. 10 This conduit 15 receives air at atmospheric temperature through a branch pipe 19 and heated air through a second branch pipe 20. Butterfly dampers 21, 22 connected by a link 23 pivoted to the dampers control these 15 openings into pipe 15. In an enlarged portion of pipe 15 is located a thermostatic vibratory vessel 24, the end walls of which are non-flexible. As shown in the drawing, the upper end wall is provided with a hub 25 having a reduced threaded end 26 which 20 passes through an opening in a screw cap 27 in conduit 15, and is secured thereto by a lock nut 28. The end of the member 25 is provided with a slot 29 to receive a tool for holding it against rotation while manipulating nut 28. The upper end wall of the vessel is thus supported and held stationary. The lower end wall of the vessel 24 is movable and is provided with a hub 30 having 25 a threaded recess for receiving a power transmitting member 31 which has a pivoted connection 32 with a lever 33. The right-hand end of this lever is pivoted to a slotted lug 34 securely held in the wall of conduit 30 35 by nut 35. The opposite end of lever 33 is provided with fork 36 for making loose connection with link 23 through pin 37 on the link. For the purpose of adjusting the system to maintain a given temperature of 40 air passing the thermostat, an adjustable spring-pressure is applied to the vessel 24. Housed in a recess in the wall of conduit is a spring 38, the lower end of which rests on a plate 39 adapted to be moved by a thumb 45 screw 40 playing in a threaded opening in the wall. The upper end of the spring 38 presses against the lower end of member 31 and is held in position by a reduced portion of member 31 entering the coil of the spring. 50 No heater for the air has been illustrated, as means for this purpose are well-known and understood in this art nor is it deemed necessary to give a specific description of the operation of this form of temperature regulator, since a description of the prin-

ciple of its operation may be found in U. S. Patent to Lund 1,017,572. It is sufficient to state that when air passes through the carbureter the thermostat operates on the change of temperature in the air surrounding it whether above or below a predetermined temperature to operate the dampers 21, 22, and thereby regulate the proportions of the warm and cold air to maintain a constant temperature of the air entering the carbureter. 75

The means which I have illustrated for controlling the supply of hydrocarbon or other liquid fuel for carbureting the air preferably consists of a thermosensitive 80 vibrating vessel 41 of the corrugated metal type located in the path of the air current at a point beyond where the liquid fuel is sprayed into the carbureter. The end walls of this vessel, like vessel 24, are non-flexible, 85 one of which is stationary and the other is adapted to move. The end wall at the right hand of the figure, the stationary wall, is provided with a shouldered hub 42 adapted to bear against the wall of the casing and is 90 furnished with a threaded end for receiving a lock nut 43 and with a slot 44 for receiving a tool for holding against rotation of the hub when the nut 43 is applied. The opposite end wall is provided with a hub 30' 95 having a threaded recess for receiving a small shaft 45 on which are formed two shoulders 46. Hub 42 and small shaft 45 are supported in bearings 47, 48, formed in the wall of section 2. The cap members for 100 these bearings are formed in the casing of section 3 as shown in the illustration. The connections between this vessel and valve 13 comprise a bell-crank lever 49 pivoted at its elbow to a lug 50 on the casting of section 105 2. To reduce friction at this bearing, the pivot support is preferably formed with a knife edge. The horizontal arm of the bell-crank lever 49 is connected at its extremity through a pivot joint 51 with the stem of 110 valve 13. The vertical arm of the lever 49 is provided with a fork straddling the shaft 45 between shoulders 46.

In order to adjust the movements of the thermosensitive element 41 and the valve 13 115 connected therewith, means are provided for applying a yielding pressure on the vessel. These means consist of a rod 52 in one end of which is a threaded recess receiving an adjusting screw 53 the stem of which passes 120 through the wall of the casting and is provided with a head for turning it. To the reduced end of rod 52 is secured the end of a spring 54. The opposite end of the spring connects with a stirrup 55 pivotally connected to the vertical arm of the bell-crank lever 49. These pivot bearings 51' are also 125 preferably of knife edge form to reduce friction.

The casing walls of section 3 are pro- 130

vided with threaded openings 55', 56 normally closed by screw plugs 57, 58. These openings are for receiving thermometers which are used for calibrating the apparatus. Near the discharge end of the carbureter is located a throttle valve 59 provided with external connections for operating it and also a spring-pressed inwardly opening valve 60 for giving access to the atmosphere.

61 is a cap closing an opening in the wall of section 1 through which to adjust valves 9 and 62 are bolts used for securing the sections together.

15 In operating my device, the proportions of vapor to air in the mixture discharged from the carbureter are maintained constant in the following manner: The parts of the device are assumed to have been assembled as illustrated and the discharge end of the carbureter to be connected with an internal combustion engine, not shown. The carbureting liquid is admitted to the reservoir 6 through supply pipe 11, and its level 20 maintained by float 7 acting on needle valve 9 which has been previously adjusted. The throttle valve 59 is set partly open and the engine is started. Plugs 57 and 58 are removed and thermometers are inserted 25 through openings 55 and 56 to indicate the temperature of the intake air and that of the carbureted mixture. Experience indicates that the temperature of the mixture of air and vapor should be maintained substantially at 110° F. for automobile practice. To maintain this temperature in the 30 space in which thermosensitive element 41 is located, it is convenient to keep the intake air at a temperature higher than this by about 30° to 35° F. Therefore, the 35 thermostatic element 24 in the intake pipe is adjusted to maintain the incoming air at about 140° to 145° F. These temperatures may be varied, however, to suit special conditions, and are merely given by way of 40 illustration. The temperatures on the thermometers are noted and if the difference in their readings is more or less than selected for standardizing the device, the 45 spring 54 is adjusted thereby admitting or cutting off the quantity of liquid vaporized into the chamber. If the difference noted is too great, the temperature of the mixture of air and vapor is too low and is to be 50 raised by reducing the admission of carbureting liquid which, in assuming the vapor state, absorbs heat from the air and lowers the temperature of the mixture. If the difference is less than desired, the 55 reverse operation is indicated. When the difference desired is attained, the thermometers are removed and the openings 55 and 60 are closed by replacing the screw plugs. Should now the demand on the carbureter 65 change, either by reason of the change in the

running of the engine or by manipulation of the throttle valve, one of two conditions may now arise in the carbureter. If the demand increases, causing a more rapid flow of air through the carbureter, an appreciable reduction of pressure may occur in the carbureting chamber, particularly in case the area of the discharge opening exceeds that of the air inlet opening, thereby resulting in a disproportionate increase in the flow 70 of the vaporizable liquid. Under these conditions, a reduction of temperature occurs around the thermostatic vessel 41, thereby causing the latter to contract and lower the needle valve 13 which then reduces the flow 75 of the vaporizable liquid to the chamber. Should, however, conditions be such that no appreciable reduction of pressure takes place in the carbureter when the throttle is opened or when there is an increased demand 80 on the carbureter by the engine, the temperature of the air and vapor rises in the carbureter chamber. The thermostatic element 41 will expand, thereby raising the needle valve to admit more vaporizable 85 liquid to meet the increased flow of air. If, on the other hand, the demand on the carbureter falls off, the temperature of the air and vapor mixture lowers and causes a contracting movement of vessel 41 and a reduction 90 of the flow of gasoline and a restoration to normal proportions of air and vapor. It will thus be seen that the predetermined proportions of air and vapor are automatically maintained and a predetermined mixture 95 is supplied under the various working conditions of the engine. Owing to the multiplicity of corrugations in the thermosensitive element 41 a very slight change in temperature causes movement of the needle valve 13 which is thereby controlled between extremely narrow limits of variation in the composition of the air and vapor mixture.

10 It is to be understood that I do not desire to be restricted in the use of my invention 110 to any particular variety or form of thermostat, yet I prefer to use the form shown, nor do I wish to be limited to the location of the connections between the thermostat and liquid fuel supply as these connections 115 may be made outside the carbureter, nor to the particular form of carbureter as other forms than that illustrated may be used.

What I claim is:—

1. In a carbureter, means for maintaining a predetermined temperature of the air supplied to the carbureter, means for supplying carbureting liquid thereto, and thermosensitive means in the path of the carbureted air for controlling the liquid supply means.

120 2. In a carbureter, means for maintaining a predetermined temperature of the air supplied to the carbureter, means for supplying carbureting liquid thereto, thermosensitive means in the path of the carbureted air for 125

130

- controlling the liquid supply means, and means adjusting said last-named means for maintaining a predetermined composition of said mixture.
5. 3. In a carbureter, means for controlling the temperature of the air entering the carbureter, valve controlled liquid fuel supply means for said carbureter, and means responsive to the temperature of the air and vapor mixture in the carbureter for controlling said valve means.
4. In a carbureter, means for controlling the temperature of the air entering said carbureter, valve controlled liquid fuel supply means for said carbureter, thermosensitive means responsive to the temperature of the air and vapor mixture in the carbureter, connections between said valve means and said thermosensitive means, and means acting through said connections to adjust the valve means.
5. In a carbureter, a conduit open to an air supply which is kept at constant temperature, means for introducing a vaporizable liquid into said conduit and thermosensitive means exposed to the mixture of air and vaporized liquid for controlling the relative supply of said liquid to said gas supply.
30. 6. In a carbureter, a conduit open to an air supply which is kept at constant temperature, means for introducing a vaporizable liquid into said conduit, thermosensitive means exposed to said mixture of air and vaporized liquid for controlling the relative supply of liquid to said gas supply, connections between said last-named means and said supply means, and means acting through said connecting means to adjust said devices.
45. 7. In a carbureter, means for controlling the temperature of air entering the carbureter, means for supplying a carbureting fluid to the carbureter, a thermosensitive vibratory vessel responding to the temperature of the resulting mixture of air and carbureting fluid and controlling said supply means.
8. In a carbureter, means for controlling the temperature of air entering the carbureter, valve controlled liquid supply means admitting carbureting fluid to the carbureter, a thermosensitive vibrating vessel responding to the temperature of the resulting mixture of air and carbureting fluid and
- controlling said supply means, and means for adjusting said valve to permit a predetermined composition of air and carbureting fluid to be maintained by said vessel.
9. In a carbureter, the combination of 60 thermosensitive means located in the air intake pipe for controlling the temperature of the incoming air, a discharge conduit controlled by a throttle valve and valve controlled means supplying the carbureter with carbureting liquid, a thermosensitive vibrating vessel in the path of the air and vapor mixture operative above and below a predetermined difference of temperature between that of the incoming air and said mixture to 65 control said supply means and maintain the composition of the air and vapor mixture constant.
10. In a carbureter, the combination of 70 thermosensitive means located in the air intake pipe for controlling the temperature of the incoming air, a discharge conduit controlled by a throttle valve and valve controlled means supplying the carbureter with carbureting liquid, a thermosensitive vibrating vessel in the path of the air and vapor mixture operative above and below a predetermined difference of temperature between that of the incoming air and said mixture to 75 control said supply means, and means for 80 adjusting said supply valve to permit a predetermined composition of air and vapor to be maintained by said vessel.
11. In a carbureter, the combination of 85 thermosensitive means located in the air intake pipe for controlling the temperature of the incoming air, a discharge conduit controlled by a throttle valve and having a valve controlled air inlet port, valve controlled means supplying the carbureter with carbureting liquid, a thermosensitive vibrating vessel in the path of the air and vapor mixture operative above and below a predetermined difference of temperature between 90 that of the incoming air and said mixture to 95 control said supply means and maintain the composition of the air and vapor mixture constant.
